UNITED STATES PATENT OFFICE.

SANFORD S. BURR, OF WINNETKA, ILLINOIS.

DESIGN FOR A FOLDING-BED FRAME.

SPECIFICATION forming part of Design No. 16,707, dated May 25, 1886.

Application filed January 29, 1886. Serial No. 190,242. Term of patent 14 years.

To all whom it may concern:

Be it known that I, SANFORD S. BURR, a citizen of the United States, residing at Winnetka, in the county of Cook and State of Illinois, have invented and produced a new and original Design for the Cases or Frames of Upright Folding Beds, of which the following is a description, reference being had to the accompanying drawing, forming part of this specification.

The drawing illustrates a perspective view of my newly-designed case or frame for upright folding beds in closed position.

It has been heretofore proposed to form the case or frame of an upright folding bed with its central portion having an enlargement or extension in the shape of the top or cover of a desk. In such form of upright folding bed, however, the lower portion of the casing or frame was of the same depth as the upper portion, which was made to represent a book-case.

The leading feature of my design consists in a frame or casing for an upright folding bed having its upper portion comparatively shallow and in imitation of a case or cabinet, and having its lower portion of greater depth than the upper portion and in imitation of a desk.

A designates the upper portion of the case or frame, which is made in imitation of a book-case or cabinet, with panels *a* and doors *a'*, this imitation of a book-case or cabinet being of less depth than the lower portion of the

case. The lower portion, B, of the case—that is to say, the part below the cabinet A—is 35 made to present the general appearance of a desk with the inclined ornamental panels *b*, and beneath it the strip or beading *b'*, the imitation drawers *b''*, and the vertical ornamental panels C and D. The upper portions of the 40 sides E of the casing or frame are narrow, as seen at *e*, having their edges of ornamental contour, as seen at *e'*, their front edges beveled, as at *e''*, and straight, as at *e'''*. Beneath the panels C and D is the base-board F. Adjoining the sides E are the head-posts G, the lower portions, *g*, of which are broader than the upper portion, and have their front edges of ornamental design, as shown. On the front edges of the posts G are the strips *g'*, somewhat narrower than the posts, and at the bottoms of the portions *g* of the posts are the panels *g''*.

I claim—

In a design for the case of an upright folding bed, the bed frame or casing having the upper portion, A, comparatively shallow, and having ornamental front in imitation of a case or cabinet, and with sides E, narrowed, as at *e*, and the lower portion, B, in imitation of a 60 desk, of greater depth than the upper portion, substantially as shown and described.

SANFORD S. BURR.
